UNITED STATES PATENT OFFICE.

LEWIS R. HEIM, OF DANBURY, CONNECTICUT, ASSIGNOR, BY MESNE ASSIGNMENTS, TO CINCINNATI GRINDERS INCORPORATED, OF CINCINNATI, OHIO, A CORPORATION OF OHIO.

METHOD AND APPARATUS FOR PRODUCING GROUND ARTICLES.

Application filed February 23, 1923, Serial No. 620,654. Renewed June 16, 1928.

This invention relates to an art and apparatus for grinding, and more particularly to an art and apparatus for grinding articles of cylindrical form.

5 One of the objects of this invention is to provide practical grinding apparatus adapted particularly for operation upon articles or objects of cylindrical form, that will be of rugged and durable construction and of dependable and efficient action. Another object is to provide apparatus of the above character that will be capable of producing highly uniform, accurate and reliable results. Another object is to provide apparatus of the 15 above character in which the degree or pressure of contact between the work operated upon and the controlling or regulating element may be regulated or predetermined at will in a simple and thoroughly practical manner, and more particularly to provide 20 apparatus in which the effect of gravity upon the work may be effectively and practically utilized to bring about whatever degree or pressure of contact between the work and the 25 controlling element may be desired. Another object is to provide apparatus of the above general nature of great flexibility of arrangement, adjustment and control and of wide range of adaptability to meet with the 30 varying requirements of practical use. Another object also is to provide a simple and practical art of grinding that may be efficiently and inexpensively carried on in practice and with accurate and uniform results.

35 Other objects will be in part obvious or in part pointed out hereinafter.

The invention accordingly consists in the features of construction, combinations of elements, arrangements of parts and in the 40 several steps and relation and order of each of the same to one or more of the others, all as will be illustratively described herein, and the scope of the application of which will be indicated in the following claims.

45 In the accompanying drawings in which is shown one of the various possible embodiments of the mechanical features of this invention,

Figure 1 is a front elevation of the grinding apparatus in assembled relation;

50 Figure 1^a is a detached fragmentary view of certain parts of the apparatus shown in Fig. 1 and, more particularly, is a front ele-

vation of the work carrier shown in a different position of adjustment;

55 Figure 1^b is a diagrammatic representation illustrative of certain actions that take place under various conditions of adjustment; and

Figure 1^c is a similar diagrammatic representation illustrating certain actions that 60 take place under various other conditions of adjustment of certain parts of the apparatus.

Figure 2 is a plan view of the apparatus shown in Fig. 1; and

65 Figure 3 is an end elevation of the apparatus as viewed from the right-hand end of Fig. 1.

Figure 4 is a detached fragmentary view on an enlarged scale of the work carrier as 70 seen on the line 4—4 of Fig. 1; and

Figure 5 is a plan view of the parts shown in Fig. 4.

75 Figure 5^a is a transverse sectional view on line 5^a—5^a, Figure 4.

Similar reference characters refer to similar parts throughout the several views of the drawings.

Referring now to the drawings and more particularly to Figs. 1, 2 and 3, there is shown 80 at 10 a main frame or standard preferably of substantially hollow construction throughout in order that certain driving mechanisms hereinafter described may be housed therein, and provided at its right-hand upper portion 85 with ways 11 extending substantially horizontally. Upon the ways 11 is supported a carriage 12 for slidable movement thereon, and preferably integrally formed with the carriage 12 are the spaced bearings 14 in which 90 is rotatably mounted a shaft 15, the forward end of which as viewed in Fig. 2 is extended to overhang the carriage 12 and to support what will hereinafter be termed a regulating wheel 16. The regulating wheel 16 may be, 95 and preferably is, composed of a suitable abrasive material, such as emery or the like, for example, and intermediate of the bearings 14 there is mounted upon the shaft 15 a pulley 17 by means of which the shaft and its 100 regulating wheel may be rotated.

Considering now the left-hand upper portion of the main frame 10, it will be seen that this portion of the frame is provided with guiding ways 18 inclined with respect to the 105 horizontal, and in Fig. 1 the inclination of the

ways 18 to the horizontal is illustratively shown as being in the neighborhood of 45° . Upon the ways 18 is slidably supported a carriage 19 suitably formed on its under side to 5 coact with the ways 18 and provided at its lower right-hand end as viewed in Fig. 1 with a pair of spaced bearings 20 (see Figs. 2 and 3) in which is rotatably supported the shaft 21. The shaft 21 is extended forwardly as 10 seen in Fig. 2, or to the left as seen in Fig. 3, to provide an end overhanging the carriage 19, and upon this overhanging end is supported a grinding wheel 22, the operative surface of which is thus positioned for coaction 15 with the regulating wheel 16 hereinabove described. Intermediate of the bearings 20 and upon the shaft 21 is mounted a pulley 23 by means of which the shaft and the grinding wheel may be rotatably driven.

20 The carriages 12 and 19 may be adjustably positioned along their respective ways 11 and 18 for purposes more clearly hereinafter set forth. The carriage 12 may be adjusted along the ways 11 as by means, for example, of the 25 hand wheel 24 operating the screw 25 which is in threaded engagement with the carriage 12. The carriage 19 may be adjustably moved or positioned along the inclined ways 18 by means of a hand wheel 26 which is preferably 30 mounted upon the forward or front part of the machine (see Fig. 1) and the wheel 26 is adapted upon manual operation to rotate the shaft 27 (see Fig. 2) upon the inner end of which is mounted a bevel gear 28. The bevel gear 28 meshes with a mating bevel gear 29 secured to the screw rod 30 suitably journaled for rotation at its respective ends in the upper portion of the main frame 10. The screw rod 30 is in turn in threaded engagement with an 35 inwardly extending lug or projection 19^a on the under side of the carriage 19 so that upon rotation of the screw rod 30 the carriage 19 with its wheel 22 will be positively moved along the inclined ways 18 and in a direction 40 depending upon the direction in which the hand wheel 26 is rotated. Moreover, it will be noted that with the mechanism thus provided for adjusting the carriage 19 along the inclined ways the carriage will be held by the 45 screw rod 30 in whatever position it is moved, without the necessity of locking the carriage in adjusted position.

In order, however, not only to facilitate the 50 manual positioning or moving of the carriage 19 on the inclined ways 18 but also to avoid discrepancies in ultimate adjustment relative to the remaining or other parts of the apparatus due to back-lash, for example, there is interposed between a suitably formed and 55 inwardly extending abutment or projection 19^a and a stationary or rigid part of the main frame 10 a heavy spring 33. This spring is 60 so proportioned as to its tendency to contract that it will substantially counterbalance the 65 effect of gravity upon the carriage 19 in tend-

ing to move the latter down the inclined ways 18, it being noted that the spring 33 is preferably positioned to act in the line of movement of the carriage 19 along the ways 18. Preferably the spring 33 is of sufficient 70 strength so that it slightly overbalances the tendency of the carriage 19 with its associated parts to slide down the inclined ways 18 so that, for example, in order to move the carriage 19 with its grinding wheel 22 downwardly toward the right as viewed in Fig. 1, the slightly overbalancing effect of the spring must be overcome through the adjusting mechanism hereinabove described and so that, therefore, back-lash in the adjusting mechanism is taken up and discrepancies in adjustment that would otherwise result therefrom avoided.

Considering now the manner in which the 85 wheels 16 and 22 are driven, it will first be noted that in the lower left-hand portion of the main frame 10 there is rotatably journaled a main driving shaft 34 the outer end of which (see Fig. 2) is provided with a pulley 35 by means of which connection to any 90 suitable source of driving power may be made, and at an intermediate point therein and in substantial alignment with the pulley 23 on the grinding wheel shaft 21 is mounted a pulley 36 connected to the grinding wheel pulley 23 as by means of the belt 37. The main driving shaft 34 is preferably rotated in clockwise direction so that with its driving connection to the grinding wheel 22, the latter will be driven in such a direction that its operative surface will be traveling substantially downwardly with respect to a point intermediate of the grinding wheel 22 and the regulating wheel 16.

In order to maintain the driving connection 105 between the pulley 36 and the grinding wheel pulley 23 throughout the movement of the latter with the carriage 19 along the inclined ways 18, there is mounted interiorly upon the main frame 10 and to act upon the loose side of belt 37 a suitable jockey pulley 38 in any suitable manner as, for example, upon a swinging arm 38^a, so as to yieldingly maintain sufficient tension in the belt 37 throughout the range of movement of the pulley 23 with the carriage 19 along the inclined ways. An idler 39 mounted upon a fixed shaft 39^a acts upon the tight side of belt 37. At this point it may be 110 noted that the main driving shaft 34 is driven at a speed sufficiently great to give the grinding wheel 22 a surface speed sufficient for effective grinding or abrasive action upon the work.

Considering now the preferred manner in 125 which the regulating wheel 16 is driven, it will first be noted that whereas the axis of the grinding wheel 22 is preferably horizontal (see Fig. 3), the axis of the regulating wheel 16 is preferably inclined not only with respect to the horizontal plane as viewed in Fig. 3, 130

but also with respect to the vertical plane passing through the axis of the grinding wheel 22 as viewed in Fig. 2. This relative inclination between the axes of the two wheels 5 may conveniently be attained by displacing the rear bearing of the two spaced bearings 14 in which the regulating wheel shaft 15 is mounted not only toward the vertical plane through the axis of the grinding wheel shaft 10 21 as viewed in Fig. 2, but also downwardly as viewed in Fig. 3, all with respect to the forward bearing of the pair of bearings 14. The angular relation between the axes of the two wheels 15 as viewed in the horizontal plane (see Fig. 2) or as viewed in the vertical plane (see Fig. 3) may, for example, be in the neighborhood of 3°.

In the lower right-hand end of the main frame 10 as seen in Fig. 1, there is journaled 20 an auxiliary shaft 40 in substantial alignment with the axis of the regulating wheel shaft 15, and upon this shaft 40 is mounted a pulley 41 which is placed in driving connection with the pulley 17 on the regulating wheel shaft 25 15 as by means of a belt 42. A jockey pulley 43 suitably mounted interiorly of the main frame 10 and bearing against the belt 42 is adapted to maintain this driving connection throughout the range of movement of the regulating wheel pulley 17 with the carriage 30 12 along the ways 11.

Upon the auxiliary shaft 40 is rotatably mounted a cone pulley 44 (see also Fig. 2) herein illustratively shown as being formed 35 in three steps. Upon the main driving shaft 34 there is mounted to be rotated therewith a complementary cone pulley, generally indicated at 45 and illustratively shown also as having three steps, and interconnecting 40 these two cone pulleys is a driving belt 46 which may be placed in driving connection with any complementary pair of steps on the cone pulleys 45 and 44 in order that the speed 45 of rotation of the cone pulley 44 as a unit may be varied at will. A jockey pulley 47 is preferably provided to insure a good driving connection. At this point it may be noted that the various jockey pulleys hereinabove referred to are merely diagrammatically 50 shown in the drawings and it will be understood that they may be mounted in any suitable manner in order to yieldingly act upon their respective belt connections.

Interposed between the cone pulley 44 and the pulley 41 is a speed-change mechanism, 55 generally indicated at 48, and adapted to be controlled as by means of the control rod 49 extending forwardly through the front part of the main frame 10 and adapted to be manually positioned as by means of the hand wheel 50. This speed-change mechanism 48 may be of any desired form and may, for example, take the form of that described in my co-pending application Serial No. 446,041, 60 filed February 18, 1921. At this point it may

be noted that the speed-change mechanism 48 is adapted upon moving the control rod 49 in one position to interpose between the cone pulley 44 and the pulley 41 on the shaft 40 suitable speed-reducing gearing in order that 70 the regulating wheel 16 may be driven through the belt 42 and from the pulley 41 at a relatively low speed in order that the work, which preferably takes the form of cylindrical articles or objects, may be uniformly rotated by the slowly traveling regulating surface provided by the wheel 16 during the grinding action thereon by the grinding wheel 22, as will be more clearly herein-after set forth. Also, the regulating wheel 80 16 is effective to bring about a continued movement of the work past the grinding wheel 22, as will also be more clearly herein-after described, and it will be noted that the speed of rotation of the regulating wheel 16 85 to vary these actions may be readily adjusted or controlled as by means of the stepped cone pulleys 45 and 44.

Since, however, the wheels 16 and 22 have to be trued or turned down as, for example, 90 by means of a suitable abradant, such as a diamond, it is desirable when such truing is brought about to rotate the regulating wheel 16 at a suitably high speed to bring about a uniform turning down or truing of its surface. 95 When this action is desired to be brought about the controlling rod 49, through the hand wheel 50, is positioned to interpose a different gear ratio between the cone pulley 44 and the driving pulley 41, or in effect to 100 eliminate the speed-reducing mechanism previously interposed therebetween, and thus to permit the regulating wheel 16 to be driven at a relatively high speed. The regulating wheel 16, when driven at a speed to control 105 the rotation of the work and also to feed the work past the grinding wheel, is driven in such direction that, with respect to a point intermediate of the grinding wheel 22 and the regulating wheel 16, the operative surface of 110 the latter travels in a direction opposite from that in which the grinding wheel surface travels. This same direction of rotation of the regulating wheel 16 may be retained when its speed is increased as above described to 115 bring about the truing of its surface.

Considering now the means whereby the work is presented to the two wheels, it will first be noted that the grinding wheel 22 is substantially housed within a suitably formed 120 protective casing 51 preferably mounted concentrically with the grinding wheel 22 and suitably formed to be secured in any suitable manner to the movable carriage 19 as, for example, as at 52. The lower right-hand end 125 of the casing 51 is open to expose the peripheral operative surface of the grinding wheel 22 for grinding action upon the work and at its lowermost right-hand portion (see Fig. 1) is provided with an extension providing 130

a supporting surface 53 inclined to the horizontal to substantially the same degree as are the guiding ways 18 upon which the carriage 19 is supported. Upon this inclined supporting surface 53 (see also Fig. 4) is supported what will hereinafter be termed a carrier frame, generally indicated at 54, provided at its forward end with a transversely and substantially downwardly extending plate 55 integrally formed therewith and adapted to cooperate with a downwardly extending flange 56 integrally formed with the casing 51 so that the carrier frame may be suitably aligned and locked with respect to one of the wheels, as by means of the cap screw 57 extending through the slot 58 in the front plate 55 and threaded into the flanged portion 56.

The carrier frame 54 is extended rearwardly as viewed in Fig. 1, or to the left as viewed in Fig. 4, in order preferably to extend between the adjacent operative surfaces of the two wheels and both forwardly and rearwardly of the two wheels. The carrier frame 54 is provided with transversely extending posts 59 and 60 preferably integrally formed therewith and one on each side of the two wheels, as is more clearly shown in the enlarged view of Fig. 5. In the lower portion of the carrier frame 54 is slidably supported a wedge-like member 61, the carrier frame 54 being suitably recessed throughout its length, as at 62 (see Figs. 4 and 5^a), to provide a guiding way inclined with respect to the supporting surface 53. The wedge-like member 61 may be moved along the inclined guiding way 62 so that its upper supporting surface 61^a, which is preferably horizontal as viewed in Fig. 4 and parallel to the supporting surface 53 upon which the carrier frame 54 rests, may be moved in a direction substantially transverse to the inclined surface 53, as viewed in Fig. 1. An adjusting screw 63 threaded into the carrier frame 54 (see Fig. 4) and manually rotatable as by the hand wheel 65, is provided with a collar 66 adapted to engage the recessed end 61^b of the wedge member 61 to bring about such slidable movement at will of the wedge member 61.

Upon the supporting surface 61^a of the wedge member 61 is supported what will hereinafter be termed a work carrier 67 provided with slots 68 and 69 extending in the general direction of the posts 59 and 60, respectively. Through these slots extend the clamping screws 70 and 71, respectively, which are threaded into the posts 59 and 60, respectively, in order that the carrier 67 may be locked in adjusted position as determined by the wedge member 61. Thus, for example, the carrier 67 may rest directly, as hereinabove described, upon the wedge member 61 so that the upper end face or work-supporting surface 72 thereof may extend in substantial parallelism with the supporting surface 53, as viewed in Fig. 4,

and it may at this point be noted that by reason of the inclined relation of the axis of the regulating wheel 16 there will exist between the path of travel of the operative surface of the regulating wheel 16 and the path of travel of the work provided by the surface 72 of the carrier 67 a fixed relative inclination which, as will be more clearly set forth hereinafter, is effective to bring about a feed of the work (indicated at 73 in Fig. 4 in the form of rolls, for example) along the carrier and in a direction to the left as viewed in Fig. 4. Since, however, it may be desirable to vary this fixed inclination in order thereby to change the rate of feed of the work 73 along the carrier, there may be interposed between the carrier 67 and the supporting surface 61^a of the wedge member 61 a shim, for example, taking the form of a tapered member 74 (see Fig. 4) in order to tilt the carrier 67 with respect to the path of travel of the operative surface of the regulating wheel 16. The slots 68 and 69 in the carrier 67 permit this tilting adjustment to be made after which the carrier 67 may be locked in position, as by means of the locking screws 70 and 71.

It will be noted, referring now to Fig. 1, that the carrier 67 is mounted upon the left-hand or upwardly inclined faces of the supporting posts 59 and 60. At the upper ends of the posts 59 and 60 are mounted the guide plates 75 and 76, respectively, the plate 75 forming with the upper face 72 of the work carrier 67 a V-shaped channel for supporting and guiding the work 73 into operative relation to the operative surfaces of the two wheels. The guiding plate 76, which, like the guiding plate 75, extends within close proximity to the regulating wheel 16, forms with the supporting surface 72 of the carrier 67 a V-shaped channel for guiding the work 73 out of operative relation with respect to the two wheels. As is clearly shown in Fig. 1, the work carrier 67 may be spaced from its supporting post, as 59 for example, as by the interposition of suitable blocks or shims 77.

The carrier frame 54 is adapted to be adjustably positioned along the inclined supporting surface 53 as viewed in Fig. 1, and turning now to Figs. 4 and 5 it will be seen that there is provided an adjusting screw 78 in threaded engagement in the forward portion of the rearwardly extending portion 56^a, upon which the supporting surface 53 is formed. The carrier frame 54 is provided with a downwardly and rearwardly extending lug 79 in which the adjusting screw 78 is rotatably mounted and held against relative axial movement therebetween as by a collar 80 and the hand wheel 81. Thus, referring to Fig. 1, it will be seen that manual rotation of the hand wheel 81 is effective to permit movement of the carrier frame 54

with its associated carrier 67 in a direction substantially coincident with the direction of the inclined ways 18. The clamping screw 57 serves to lock the carrier frame in its adjusted position.

Considering now the operation of the apparatus and certain of the actions that take place, it may first be again noted that the regulating wheel 16 and the grinding wheel 22 are rotated in the directions of the arrows shown in Fig. 1 to provide operative surfaces which travel in opposite directions with respect to the work carrier 67 interposed therebetween. The grinding wheel 22 through the driving apparatus hereinabove described is driven at a suitable grinding speed, and the regulating wheel 16 is driven through the speed-change mechanism 48 at a relatively low speed in order to control the rotation of the cylindrical work presented to the wheels. The work 73 which may, for example, take the form of rolls, is carried to the operative surfaces of the two wheels in the substantially V-shaped guiding channel formed by the guiding plate 75 and the supporting surface 72 of the carrier 67 and is thus fed up to the operative surfaces of the two wheels. Upon the work 73 reaching the left-hand end of the guiding plate 75 as viewed in Fig. 4, the V-shaped guiding channel for the work is continued by the supporting surface 72 and the moving operative surface of the regulating wheel 16. The work 73 is thus supported not only by the surface 72 of the carrier 67 but also in part by the moving surface of the regulating wheel 16 which thus forms the complement or continuation of the substantially V-shaped guiding channel. The work is thus uniformly and constantly rotated and by reason of the relative inclination that exists between the path of travel of the operative surface of the regulating wheel 16 and the path of travel of the work 73 as predetermined by the carrier 67 the work is also fed along the carrier 67. During this action the grinding wheel 22 is operative to effect a grinding action upon the work as the latter is rotated and moved along. As the work emerges from between the operative surfaces of the two wheels the guiding plate 76 forms with the carrier 67 a V-shaped channel for guiding the work out of operative relation from the two wheels.

During the action that takes place as above described it will be seen that the regulating wheel surface acts in part to support the work for grinding action by the grinding wheel 22 and thus the weight of the work itself is effectively utilized to insure an intimate frictional contact with the regulating wheel surface and thus make certain a positive control of the rotation of the work, it being noted that a component of the weight of the work itself is effective to urge the work toward, and into contact with, the operative surface of the

regulating wheel 16. This component, moreover, may be varied at will and thus the degree or pressure of contact between the work and the operative surface of the regulating wheel may be predetermined as desired. 70

In Fig. 1^b are diagrammatically shown two of the various adjustments that may be made to bring about a different degree of contact between the work and the regulating wheel 75 surface. It may first be noted that the regulating wheel 16 presents an operative surface, the inclination of which to the vertical (as determined by the tangent drawn thereto) varies progressively from a minimum at a point 80 in the horizontal plane through the axis of the wheel to a maximum at a point in the vertical plane through the axis of the wheel. These points are indicated, respectively at *a* and *b* in Fig. 1^b. At *c* is shown diagrammatically a work carrier acting with the surface of the wheel 16 to support the work 73 at a point in the operative surface thereof at which the inclination is as determined by the tangent *d*—*e*. Assuming that the work carrier *c* provides a work-supporting surface which is substantially radial, the component of the weight of the work 73 acting to urge the work toward the regulating wheel surface will be a function of the angle made by the tangent *d*—*e* to the horizontal and, in effect, will be proportional to the cosine of the angle *e*—*d*—*f*. 90

As the work carrier *c* is adjustably positioned with respect to the operative surface 100 of the regulating wheel 16 to provide a path of travel for the work 73 adjacent a point in the operative surface the inclination of which to the horizontal is different, the force acting to urge the work 73 toward the regulating wheel surface will be changed, and at *c'* the work carrier is shown positioned so as to present the work 73 to the regulating wheel surface at a point where its inclination is *d'*—*e'*. 105 Assuming that the supporting surface of the carrier *c'* is substantially radial, the component of the weight of the work 73 now acting to urge the work toward the regulating wheel surface will be proportional to the cosine of the angle *e'*—*d'*—*f'*, which cosine varies from 110 zero to one as the work 73 is positioned at successive points from the point *a* to the point *b* in the periphery of the wheel. Accordingly, the work may be urged toward the regulating wheel surface by a pressure which may be adjusted from zero at the point *a* to a value equivalent to the total weight of the work 73 at the point *b*. 115

Turning now to Fig. 1 of the drawings, it will be seen that the work carrier 67 may be 125 adjustably positioned with respect to substantially a like portion of the operative surface of the regulating wheel 16 as is diagrammatically shown in Fig. 1^b. Thus, for example, the regulating wheel 16 may be moved 130

to the right by adjustably positioning the carriage 12 on the ways 11 by means of the hand wheel 24, and the grinding wheel 22 with its carriage 19 moved downwardly in the ways 18, thus in effect decreasing the inclination of the line joining the axes of the two wheels 16 and 22 as viewed in this figure. The carrier 67 may be adjustably positioned by operating the hand wheel 65 (see Figs. 4 and 5) to move the carrier along the supporting posts 59 and 60 and thus to vary the inclination of that part of the operative surface of the regulating wheel that acts to assist in supporting the work 73 relative to the grinding wheel. Likewise, it will also be noted that the grinding wheel 22 may be moved upwardly along the inclined ways 18, thereby in effect to raise the grinding wheel relative to the regulating wheel, and that the regulating wheel 16 may be moved to the left along the ways 11 to increase the inclination of the line or plane passed through the axes of the two wheels as seen in Fig. 1. The work carrier 67 may be moved upwardly with respect to the supporting posts 59 and 60 thereby to provide a path of travel for the work along a portion of the regulating wheel surface, the inclination to the horizontal of which is less, thereby to increase the effect of gravity in holding the work against the regulating wheel surface. Thus it will be seen that the wheels and the carrier may be adjusted relatively to one another in effect to swing or move the grinding wheel 22, as well as the carrier 67, through loci that are substantially concentric with the operative surface of the regulating wheel 16, and that these relative adjustments may be made throughout a sufficient range to adjust the effect of gravity or to vary the component of the weight of the work supported by the regulating wheel to any desired value. Thus, referring again to Fig. 1^b, it will be seen that as the work support is adjustably positioned to change at will the reaction of the regulating wheel surface in supporting the work 73, the grinding wheel 22 may be likewise relatively adjusted in effect to follow up the various adjustments given the work support.

Referring now to Fig. 1 again, it will be noted that the upper supporting surface 72 of the carrier 67 is inclined with respect to the operative surface of the regulating wheel 16. The component of the weight of the work 73 supported by the regulating wheel surface 72 may also be adjusted or varied at will by changing the inclination of the supporting surface 72 of the work support 67, and in effect this component, which represents the pressure or force with which the work is urged toward the regulating wheel surface or is held in contact therewith, may be varied throughout a wide range. In Fig. 1^c is diagrammatically illustrated the action that results from an assumed change in inclination of the supporting surface 72 of the carrier 67.

Turning now to Fig. 1^c, the work carrier 67 is shown adjacent the regulating wheel 16 and the supporting surface thereof is illustratively shown as being inclined along the line *j*—*k*. The weight of the work 73 is represented by the vector *W* and, assuming the inclination of the supporting surface along the line *j*—*k* and resolving the vector *W* into the two components representing the reaction of the carrier 67 and the reaction of the supporting surface of the wheel 16, it will be found that the vector *o*—*l* represents the component of the weight supported by the carrier 67 and the vector *o*—*n* represents the component of the weight for the force with which the work 73 is urged toward the regulating wheel surface. It will be noted that the component *o*—*n* is slightly less than the vector *W*. Let it be assumed now that the carrier 67 has the inclination of its supporting surface changed from that illustrated by the line *j*—*k* to that denoted by the line *p*—*r*; and again resolving the vector *W* into its respective components it will be found that the vector *o*—*s* represents the component of the weight supported by the work carrier 67 and the vector *o*—*t* will represent the component of the vector *W* with which the work is held in contact with the regulating wheel surface. The component *o*—*t*, it will be noted, is greater than the vector *W*, and it will thus be seen that by varying the inclination of the supporting surface of the carrier 67 the pressure or force with which the work is urged toward the regulating wheel surface may be made equal to, less than, or greater than the weight of the work itself.

In Fig. 1^a, which is a fragmentary front elevation of parts shown in Fig. 1, it will be seen that the carrier 67 has been inclined with respect to the supporting posts 59 and 60 as by the interposition of a tapered or wedge-like block or shim 82 in order to give the work 73 of the carrier 67 an inclination differing from that shown in Fig. 1 and in order to bring about a variation of the force with which the work 73 is held in contact with the regulating wheel surface as diagrammatically shown in Fig. 1^c. It will be noted, however, that with the arrangement of the carrier 67 as hereinbefore described the carrier 67 may be adjustably positioned as by means of the controlling hand wheel 65 (see Fig. 4) to bring about a change, diagrammatically shown in Fig. 1^b, and that by combining with such an adjustment a change in the inclination of the supporting surface of the carrier 67, as is illustratively shown in Fig. 1^a and diagrammatically shown in Fig. 1^c, the effects of these two adjustments may be combined to permit a predetermination to any desired value of the pressure or force with which the work is held in contact with the moving controlling surface of the regulating wheel 16. Thus it will be seen, that the

intimacy of contact between the work and the moving controlling surface of the regulating wheel 16 may be adjusted at will to insure for the varying requirements of practical use a positive control of the rotation of the work while it is acted upon by the grinding wheel and ground to accurate cylindrical form.

At this point it may be noted that the frictional contact between the work and the regulating wheel surface may depend on various factors such as, for example, the rate of travel of the operative surface of the regulating wheel, the nature of the material operated upon, hereinabove assumed, by way of example, as consisting of hardened rolls such as are employed in roller bearings, the size or diameter of the work operated upon, and friction thereof on the carrier, and various other factors. By means of the adjustments hereinabove described the work may be urged toward the regulating wheel surface at any desired pressure and thus effective control of the rotation of the work is brought about irrespective of the various factors which might otherwise tend to undesirably affect the control of the rotation of the work. It may at this point also be noted that the spacing between the operative surfaces or lines of contact of the work with these surfaces may be readily adjusted by adjusting either of the wheels along its respective supporting ways and that also the carrier frame 54 on which the carrier 67 is supported may be readily positioned as by means of the hand wheel 81 at the desired point intermediate of the two wheels.

As hereinabove noted, the path of travel of the operative surface of the regulating wheel 16 is inclined relative to the path of travel of the work as determined by the carrier 67 and thus the movement of the work along the carrier 67 may be brought about during the control of the rotation thereof by the regulating wheel and during the grinding action thereon by the grinding wheel 22. Moreover, it may be noted that this relative inclination may be maintained, thus to bring about the feeding action, throughout the entire range of adjustment of the carrier 67 and of the grinding wheel 22 relatively to the operative surface of the regulating wheel and in effect about the axis thereof, as hereinabove described. Thus an effective feeding action for all adjustments is maintained. Also, as above noted, the rate of feed thus provided may be varied by tilting the carrier 67 to increase or decrease the existing relative inclination above noted, thus to vary the rate of feed at will. Moreover, the stepped cone-pulleys 44 and 45 may also be utilized to vary the rate of drive of the regulating wheel and thus also to adjust or vary the rate of feed as well as the rate of rotation of the work.

It will be noted that suitable means are provided for supplying the wheels with a suitable cooling fluid, such as water, for example, as by means of the valve 83 (see Fig. 1) and that the wheels are suitably encased, the grinding wheel as by the casing 51, and the regulating wheel as by the casing 84, in order thus not only to protect the operators but also to prevent the spraying of the cooling fluid. The casing 84 in which the regulating wheel 16 is housed is, moreover, cut away to a sufficient extent to permit the relative adjustments of the two wheels and the work carrier to be made and which, as hereinabove noted, may be considered as including a variation of the inclination of the line or plane passed through the axes of the two wheels, as viewed in Fig. 1.

Associated with each of the wheels are suitable truing devices, indicated in Fig. 1 at 85 and 86, adapted for truing or turning down action upon the grinding wheel 22 and the regulating wheel 16, respectively. These truing devices or tools, which may take the form of a suitable abradant, such as a diamond, for example, may be controlled or operated by suitable mechanisms, generally indicated at 87 and 88, respectively, and may conveniently take the form of mechanism described in my co-pending application Serial No. 619,373, filed February 16, 1923. In this connection it might at this point be noted that when the regulating wheel is to be trued it is preferably driven at a relatively high speed as distinguished from the relatively low speed with which it operates normally, as hereinabove described. Such a change in the rate of speed may be brought about, for example, as by the speed-change mechanism 48 controlled by the hand wheel 50, as hereinabove described.

It will thus be seen that there has been provided in this invention an art and apparatus for grinding in which the several objects of this invention, as well as many advantages, are achieved. It will be seen that the apparatus is essentially of a thoroughly practical nature and is characterized by a wide flexibility of control and adjustment in order that an effective and positive control of the work may be exercised to meet the various requirements and conditions demanded by practical use. It will, moreover, be noted that the degree or pressure of contact of the work with the regulating surface may be predetermined at will or adjusted so that efficient and accurate grinding resulting from a positive control of the work by the regulating wheel may be attained.

As many possible embodiments may be made of the mechanical features of the above invention and as the art herein described might be varied in various parts, all without departing from the scope of the invention, it is to be understood that all matter herein set

forth or shown in the accompanying drawings is to be interpreted as illustrative and not in a limiting sense.

I claim as my invention:

5. 1. A centerless grinding mechanism comprising, in combination, a rotary grinding wheel; a regulating support moving at relatively low speed and presenting a peripheral surface having points or lines of possible operative contact with the work, the tangents to said surface passing through such points or lines inclining progressively to the vertical from substantially 0° to substantially 90° ; the said grinding wheel and said regulating work support at their work-engaging points travelling in opposite directions; a work carrier positioned between said grinding wheel and said regulating support; and means for adjusting the relations of the said regulating support and the work carrier to change the relation of the work carrier and the regulating support back or forth in the general direction and within substantially the range of the said progressive inclination of the tangents and for adjusting the grinding wheel substantially at right angles to said direction, toward and from the regulating support.

2. In apparatus of the character described, in combination, a grinding wheel, a regulating wheel coacting therewith and rotatable at relatively low speed, said wheels being adapted to present adjacent operative surfaces travelling in opposite directions, a work carrier interposed therebetween and having a work supporting surface inclined to the vertical and toward the operative surface of said regulating wheel to cause a component of the thrust of the grinding wheel on the work to be exerted in a direction toward said regulating wheel, thereby to urge the work against said regulating wheel, and means for changing the inclination of said supporting surface of said carrier to predetermine the magnitude of the said component with which the work is urged against the regulating wheel.

3. In apparatus of the character described, in combination, a regulating wheel rotatable at relatively low speed and presenting an operative surface to cylindrical work presented thereto, a grinding wheel, said wheels being adapted to present operative surfaces travelling in opposite directions with respect to an intermediate point, a work carrier extending between said wheels and adapted to guide cylindrical work along a predetermined path relative to the operative surfaces of said two wheels, and means mounting said work carrier and said regulating wheel relative to one another to permit relative adjustment therebetween in such manner that their contact with the work may present lines of gravity opposing resistance intersecting at an angle producing a component of reaction on each other and provide for variation of such angle

to permit variation of such component by a movement at an angle to the direction at which gravity acts.

4. In apparatus of the character described, in combination, a regulating wheel rotatable at relatively low speed and presenting a peripheral operative surface to work presented thereto, a work carrier associated therewith and adapted to provide a predetermined path of travel for work relative to the operative surface of said regulating wheel, said carrier having a work supporting surface inclined toward the surface of said regulating wheel, a grinding wheel positioned at the other side of said work carrier for grinding operation on said work, said wheels being adapted to present operative surfaces travelling in opposite directions, and means for relatively adjusting said wheels and for adjusting said carrier relative to said wheels to vary the relative position of the grinding wheel and the work carrier circumferentially of the regulating wheel, while maintaining the same radial distance between the wheels if this be desired.

5. In apparatus of the character described, in combination, a grinding wheel, a regulating wheel rotatable at relatively low speed, a work carrier extending therebetween and providing a predetermined path of travel for work relative thereto, said wheels being adapted to present operative surfaces travelling in opposite directions, means mounting said grinding wheel at a greater elevation than that of said regulating wheel and adapted to permit adjustment thereof toward or away from said regulating wheel along a plane making an acute angle to the horizontal, and means mounting said work carrier to permit adjustment thereof in directions substantially coincident with the direction in which said grinding wheel may be adjusted and also substantially transversely thereto.

6. In apparatus of the character described, in combination, a grinding wheel, a regulating wheel rotatable at relatively low speed, a work carrier interposed therebetween, said wheels being adapted to provide operative surfaces travelling in opposite directions with respect to said work carrier, means mounting one of said wheels and adapted to permit adjustment thereof toward or away from the other along a plane inclined to the horizontal, and means mounting the other of said wheels adapted to permit adjustment thereof toward or away from the other along a plane substantially horizontal.

7. In apparatus of the character described, in combination, a grinding wheel, a regulating wheel rotatable at relatively low speed, a work carrier interposed therebetween, said wheels being adapted to provide operative surfaces travelling in opposite directions with respect to said work carrier, means mounting said grinding wheel and adapted to permit

adjustment thereof toward or away from said regulating wheel along a plane inclined to the horizontal, and means mounting said regulating wheel and adapted to permit adjustment thereof toward or away from said grinding wheel along a plane substantially horizontal.

8. In apparatus of the character described, in combination, a main frame having guiding ways substantially horizontal and other guiding ways inclined with respect thereto, a grinding wheel, a regulating wheel rotatable at relatively low speed, said wheels being adapted to present operative surfaces traveling in opposite directions, a carriage rotatably mounting said grinding wheel and slidably supported on one of said guiding ways, a carriage for rotatably supporting said regulating wheel for coaction with said grinding wheel and slidably mounted upon the other of said ways, and a work carrier extending between said wheels and adjustable to substantially accord to the relative adjustments of the points of contact of said wheels with the work and providing a predetermined path of travel for work relative to the operative surfaces of said two wheels.

9. In apparatus of the character described, in combination, a main frame having guiding ways substantially horizontal and other guiding ways inclined with respect thereto, a grinding wheel, a regulating wheel rotatable at relatively low speed, said wheels being adapted to present operative surfaces traveling in opposite directions, a carriage for rotatably supporting said grinding wheel and slidably mounted on said inclined ways, a carriage for rotatably supporting said regulating wheel for coaction with said grinding wheel and slidably supported in said substantially horizontal ways, and a work carrier extending between said wheels and adjustable to substantially accord to the relative adjustments of the points of contact of said wheels with the work and providing a predetermined path of travel for work relative to the operative surfaces of said two wheels.

10. In apparatus of the character described, in combination, a main frame provided with ways inclined to the horizontal, a regulating wheel rotatable at relatively low speed, a grinding wheel, said wheels being

adapted to present operative surfaces traveling in opposite directions, a work carrier positioned between said wheels adapted to provide a predetermined path of travel for work relative to the operative surfaces of said wheels, a carriage rotatably supporting one of said wheels and slidably mounted on said inclined ways, means associated with said carriage adapted substantially to counterbalance said carriage on said inclined ways, and means for adjustably positioning said carriage along said ways.

11. In apparatus of the character described, in combination, a main frame provided with ways inclined to the horizontal, a regulating wheel rotatable at relatively low speed, a grinding wheel, said wheels being adapted to present operative surfaces traveling in opposite directions, a work carrier positioned between said wheels adapted to provide a predetermined path of travel for work relative to the operative surfaces of said wheels, a carriage rotatably supporting one of said wheels and slidably mounted on said inclined ways, spring means acting upon said carriage to substantially counterbalance the effect of gravity thereon, and means for adjustably positioning said carriage along said ways.

12. In apparatus of the character described, in combination, a grinding wheel, a regulating wheel rotatable at relatively low speed, a work carrier interposed therebetween, said carrier and said regulating wheel providing adjacent surfaces inclined toward one another and to the vertical to form a work supporting trough and said wheels being adapted to provide adjacent operative surfaces travelling in opposite directions, and means adapted to permit relative adjustment between said wheels and said carrier to vary the inclination relative to the vertical of a line passing through the axes of the two wheels and to vary the relative inclination between the surfaces forming said work supporting trough.

In testimony whereof, I have signed my name to this specification this seventh day of February, 1923.

LEWIS R. HEIM.
